UNITED STATES PATENT OFFICE.

BENNARD H. POMEROY, OF ROCHESTER, NEW YORK, ASSIGNOR, BY MESNE ASSIGNMENTS, TO R. E. DIETZ COMPANY, OF NEW YORK, N. Y., A CORPORATION OF NEW YORK.

LAMP-REFLECTOR.

1,198,657.

Specification of Letters Patent. Patented Sept. 19, 1916.

Application filed June 23, 1914. Serial No. 846,780.

To all whom it may concern:

Be it known that I, BENNARD H. POMEROY, a citizen of the United States, residing at Rochester, in the county of Monroe 5 and State of New York, have invented a new and useful Improvement in Lamp-Reflectors, of which the following is a specification.

This invention relates to that class of reflectors which are employed in headlights and other vehicle lamps for directing the light forwardly upon the road and which are approximately of parabolic form and have the source of light, whether electric 15 bulb, gas, or oil flame, arranged within the reflector approximately in the focus thereof.

The object of this invention is the production of a reflector of this general character in which the illuminated field is somewhat larger in area than in a true parabolic reflector, in other words, in which the light is spread somewhat, and in which the intensity of the light is somewhat reduced, thereby avoiding an excessive or objectionable glare, and which permits the production of a very small and compact headlight or lamp having the necessary illuminating capacity, both as to distance or range and field or area of illumination.

30 In the accompanying drawings: Figure 1 is a longitudinal section of an electric headlight or vehicle lamp embodying this improved reflector. Fig. 2 is a side elevation of the reflector detached. Fig. 3 is a front elevation of the same.

10 represents the casing or body of an electric headlight of any ordinary or well known construction. 11 represents the reflector arranged within the same and comprising a main or body portion 12, which is approximately parabolic in form, and a front portion 13 which constitutes an annu-

lar enlargement having a concave inner face which curves outwardly and forwardly from the front end of the body portion 12 and 45 which terminates preferably in a flat or radial front flange 14 projecting outwardly from the enlarged front portion and connecting the reflector with the casing.

The concave annular front enlargement 50 of the reflector spreads the light to a certain extent and increases the area of the illuminated field accordingly, and it also dims the light to a certain extent and obviates an objectionable glare or intensity of the light. 55

15 represents an electric light bulb arranged within the body portion 12 of the reflector approximately in the focus thereof. Any other suitable source of light, such as a gas lamp or oil lamp, may, of course, be 60 employed and the body of the reflector and the casing be constructed in a well known manner to accommodate such lamp.

16 represents the front glass, 17 the frame in which the same is mounted, and 18 the 65 annular reflecting ring in said frame, all of any suitable or well known construction.

I claim as my invention:

A lamp comprising a casing, an approximately parabolic reflecting body adapted to 70 contain the source of light arranged within said casing, an annular concave reflecting enlargement curving outwardly and forwardly from the front end of said parabolic body and extending beyond the source of light 75 and means for connecting the enlargement with the casing.

Witness my hand in the presence of two subscribing witnesses.

BENNARD H. POMEROY.
